DESIGN FOR A SHIP ORNAMENT

Abraham Solomon, New York, N. Y., and Eugene Volynkine, Paris, France, assignors to National Silver Deposit Ware Co. Inc., New York, N. Y., a corporation of New York

Application January 27, 1938, Serial No. 74,592

Term of patent 3½ years

To all whom it may concern:

Be it known that we, Abraham Solomon, a citizen of the United States, residing at New York city, county and State of New York, and Eugene Volynkine, a citizen of the Union of Socialist Soviet Republics, residing at Paris, France, have invented a new, original, and ornamental Design for a Ship Ornament, of which the following is a specification, reference being had to the accompanying drawing, forming part thereof.

Figure 1 is a perspective view taken somewhat from the rear of a ship ornament showing our new design; and

Figure 2 is a perspective view taken somewhat from the front.

We claim:

The ornamental design for a ship ornament, substantially as shown.

ABRAHAM SOLOMON.
EUGENE VOLYNKINE.
